UNITED STATES PATENT OFFICE.

BAYARD M. HORTER, OF KINGSTON, PENNSYLVANIA, ASSIGNOR TO THE CUTLER-HAMMER MFG. CO., OF MILWAUKEE, WISCONSIN, A CORPORATION OF WISCONSIN.

CONTROLLER FOR POWER-DRIVEN PUMPS.

Application filed December 15, 1922. Serial No. 607,086.

This invention relates to controllers for power driven pumps, particularly centrifugal or other pumps which require priming, preparatory to pumping.

5 An object of the invention is that of providing an advantageous and improved controller for such pumps and their associated priming means.

Another object is that of providing such 10 a controller wherein provision is made for initiating action of the priming means, and also terminating such action automatically but terminating such action only after starting of the pump.

15 Another object is that of providing against starting of the pump except when fully primed and also for stopping of the pump upon loss of suction thereof and also upon given accretion of the pressure developed 20 thereby.

Other objects and advantages will hereinafter appear.

In the accompanying drawing, consisting 25 of a single figure, is illustrated schematically and diagrammatically one of the embodiments which the invention may assume in practice.

In the drawing is illustrated a pump 1 having a driving motor 2 to discharge the 30 contents of a sump, receptacle or tank 3.

An auxiliary pump 4, which may be preferably of the dry vacuum type, is adapted to be driven by a second motor 5 for priming the pump 1. To such end a stand pipe 6 is 35 provided to extend downward within the sump 3 to substantially the same level as the bottom of the intake of the pump 1, and also to extend upward an appreciable distance above the highest portion of the casing of 40 said pump. Pipes 7 and 8 serve to connect the stand pipe 6 with the intake of pump 4 and the delivery of pump 1 respectively.

An electro-responsive valve 9 and a check 45 valve 10 serve to control the passage through pipe 8 and the delivery passage of pump 1 respectively, the former valve being closed and the latter being open during normal pumping and such relation being reversed for priming.

50 A float operated switch 11 serves in conjunction with a relay 12 to control starting of the priming motor 5 and also serves in conjunction with pressure operated switches 13, 14 and 14^a to control the action of the

pumping motor 2 through a conventional 55 form of self starter which may include a main switch 15 and an accelerating switch 16, the former having an auxiliary contact 15^a controlling the energizing circuit of relay 12 to effect stopping of the priming motor 60 but only upon closure of said main switch.

Pressure responsive switch 13 is arranged in the closing circuit of main switch 15 and is adapted to close and effect energization of such circuit when, due to action of the pump 65 4 the pressure within the stand pipe has been so far reduced as to insure priming of the pump 1 by water lifted through the intake of the latter.

Pressure responsive switches 14 and 14^a 70 are arranged in the maintaining circuit of main switch 15, the former being normally closed and being adapted to open and interrupt said maintaining circuit when the pressure at the intake of pump 1 attains a given 75 minimum value. Pressure responsive switch 14^a on the other hand is biased, by gravity or otherwise, to open position but is adapted to close when the discharge pressure of pump 1 attains a given minimum value and to remain closed so long as such minimum value 80 of the discharge pressure is maintained.

The valve 9 is adapted to be normally closed under a gravity bias and also by the pressure of pump 1. However, said valve is 85 provided with an opening coil arranged to be energized when and only so long as the closing coil of relay 12 is energized.

The various elements being in the relations illustrated, the operation of the device 90 and the circuit connections which are important herein may be described as follows: Upon predetermined rise in level of fluid in the sump 3, float operated switch 11 closes and completes the energizing circuits of 95 relay 12 and valve 9, which circuit may be traced from line L² by parallel conductors 19 and 20 through the operating coils of said relay 12 and valve 9, thence by parallel conductors 21 and 22 to common conductor 23 100 and through float switch 11, thence by conductor 24 through auxiliary contacts 15^a of the main switch to line L³.

Relay 12 thereupon closes and valve 9 opens, the former connecting motor 5 to its 105 supply lines and the latter opening communication between stand pipe 6 and pump 1, whereupon priming pump 4 acts to reduce

the pressure in stand pipe 6 and within the casing of pump 1, causing the fluid in the sump to rise within the aforementioned regions of reduced pressure.

5 Pressure responsive switch 13 is calibrated to respond only after the aforementioned reduction in pressure has attained a value such as to insure filling of the casing of pump 1 by the fluid so elevated. Hence 10 upon attainment of such predetermined condition of reduced pressure said switch 13 closes and completes the energizing circuit of main switch 15, said circuit extending from line L² through the operating coil of 15 said switch thence by conductor 25 through switch 13 and by conductor 26 to line L³.

Main switch 15 thereupon closes and connects motor 2 to its supply lines for starting pump 1. Also said main switch in closing 20 opens its auxiliary contacts 15^a thereby permitting valve 9 to close cutting off communication between pump 1 and stand pipe 6 whereupon the reduced pressure within the latter persists and maintains switch 13 closed 25 while the increased pressure developed by operation of the pump 1 causes closure of switch 14^a. Relay 12 is also de-energized through opening of auxiliary contacts 15^a, thereby stopping priming motor and pump 30 5 and 4.

Main switch 15 upon closing also completes a maintaining circuit for itself, said circuit extending from line L² through the operating coil of said switch as formerly traced, 35 thence by conductor 27 through auxiliary contacts 15^b of switch 15 by conductor 28 through pressure responsive switch 14, which is normally closed, by conductor 29 through pressure responsive switch 14^a and thence by 40 conductor 30 to line L³.

The self starter thereafter functions in a conventional manner for bringing motor 2 and pump 1 up to speed.

Pump 1 now continues to operate until as 45 a result of lowering of the level of liquid in the sump, or other cause, the pressure at the pump intake falls below the aforescribed value at which the switch 14 is set to respond, whereupon said switch opens and 50 interrupts the maintaining circuit of main switch 15, which also opens and interrupts the energizing circuit of switch 16 which likewise opens and disconnects motor 2 from circuit, whereupon pump 1 stops and the 55 various parts assume or resume the relative positions illustrated.

If during pumping the pump 1 loses suction the delivery pressure of course falls below the value at which switch 14^a is set 60 to respond, whereupon said switch is adapted to open and interrupt the maintaining circuit of main switch 15 for stopping the pump in a manner similar to that just described.

65 From the foregoing it is apparent that the

pump 1 is started only after the pressure condition in the stand pipe is such as to insure that said pump is fully primed, whereas the action of the priming pump is continued until closure of the main switch. 70 Moreover the action of pressure responsive switches 14 and 14^a provides for automatic stopping of the main pump either upon attainment of a given low level of the sump liquid or whenever as a result of abnormally 75 high or low values of intake pressure the pump is unable to function properly. The main pump control effected is thus dependent upon and responsive to the pressure conditions obtaining within the pumping system, whereby an exceedingly certain and reliable control is provided.

It is also to be understood that the functions of the priming pump 4 are not limited to priming of a single main pump but on the contrary a plurality of pumps similar to the pump 1 may be arranged to be primed either jointly or individually by a single priming pump in association with control means similar or analogous to that 90 aforescribed. However, where a plurality of main pumps are to be so primed individually it is ordinarily preferable to provide individual stand pipes for said pumps, to be selectively connected with the priming 95 pump. Also if desired the main pumps may be subjected sequentially to automatic priming and starting as aforescribed and the sequential action may be controlled as by 100 variations in the rate and character of the change in liquid level following starting of the first pump.

What I claim as new and desire to secure by Letters Patent is:

1. In a controller for hydraulic pumps, 105 the combination with driving and control means and independently driven priming means for the pump, of control means for said priming means providing for starting thereof prior to starting of said pump and 110 for stopping of said priming means but only upon given operation of said pump control means.

2. In a controller for hydraulic pumps, 115 the combination with driving means and independently driven priming means for the pump, of means providing for initiating operation of said priming means, means for starting said pump driving means only after positive priming of the pump, and means 120 for stopping of said priming means but only upon given operation of said pump starting means.

3. In a controller for hydraulic pumps, 125 the combination with driving means and independently actuated priming means for the pump, of means subjected to control in accordance with the degree of action of said priming means for causing starting of said driving means for the pump and associated 130

- pressure responsive means providing for stopping of said pump under predetermined conditions of pump pressure.
4. In a controller for hydraulic pumps, the combination with driving means and independently actuated priming means for the pump, of pressure responsive means for starting said pump upon predetermined activation of said priming means, means for terminating action of said priming means upon given operation of the pump starting means, and means, including sets of independently responsive means, for causing stopping of said pump automatically under differing pressure conditions.
5. In a controller for a hydraulic pump having driving means and an independently driven vacuum priming pump, the combination with fluid level operated means for starting said priming pump, of means including a valve, enabling said priming pump to effect and maintain a reduced pressure within the main pump for drawing priming fluid therewithin, reduced pressure responsive means for insuring priming of the main pump prior to starting and pressure responsive means for stopping the main pump.
6. In a controller for a hydraulic pump having driving means and an independently driven vacuum priming pump, the combination with fluid level operated means for starting said priming pump, of means including a valve enabling said priming pump to effect and maintain a reduced pressure within the main pump for drawing priming fluid therewithin, pressure responsive means providing for starting of the main pump under such conditions of reduced pressure as to insure priming thereof, means for ar- resting action of said second mentioned means upon starting of said main pump, and means for stopping said priming pump but only after given operation of the main pump starting means.
7. In a pump controlling mechanism, the combination of a rotary pump; a motor driving said pump; mechanism controlling said motor; a suction priming means connected to the rotary pump; and means actuated by the suction pressure controlling said mechanism.
8. In a pump controlling mechanism, the combination of a rotary pump; a motor driving said pump; mechanism controlling said motor; a suction priming means connected to the rotary pump; devices for closing the connection at the completion of the priming of the rotary pump; and means actuated by the suction pressure controlling said mechanism to start the motor after the connection is closed.
9. In a pump controlling mechanism, the combination of a rotary pump; a suction priming pump connected to the rotary pump; and controlling mechanisms for said
- pumps comprising means actuated by the suction pressure of the suction pump starting the rotary pump.
10. In a pump controlling mechanism, the combination of a rotary pump; a suction priming pump connected to the rotary pump; and controlling mechanisms for said pumps comprising means actuated by the suction pressure of the suction pump starting the rotary pump and stopping the suc- 75
11. In a pump controlling mechanism, the combination of a rotary pump; a suction priming pump connected to the rotary pump; and controlling mechanisms for said pumps comprising means actuated by a liquid level starting the suction pump and actuated by suction pressure from the suction pump to start the rotary pump. 80
12. In a pump controlling mechanism, the combination of a rotary pump; a suction priming pump connected to the rotary pump; and controlling mechanisms for said pumps comprising means actuated by a liquid level starting the suction pump and ac- 90
- tuated by suction pressure from the suction pump to start the rotary pump and stop the suction pump.
13. In a pump controlling mechanism, the combination of a rotary pump; a suction priming pump connected to the rotary pump; and controlling mechanisms for said pumps comprising means actuated by a liquid level starting the suction pump and ac- 95
- tuated by suction pressure from the suction pump to start the rotary pump and stop the suction pump and actuated by a liquid level stopping the rotary pump. 100
14. In a pump controlling mechanism, the combination of a rotary pump; a motor 105
- driving said pump; mechanism controlling said motor, said mechanism having starting and normal running positions; a suction priming pump connected to the rotary pump; and fluid pressure actuated means 110
- controlling said mechanism.
15. In a pump controlling mechanism, the combination of a rotary pump; a motor driving said pump; mechanism controlling said motor, said mechanism having starting and normal running positions; a suction priming pump connected to the rotary pump; and fluid pressure actuated means 115
- responsive to the action of the suction pump controlling said mechanism. 120
16. In a pump controlling mechanism, the combination of a rotary pump; a motor driving said pump; mechanism controlling said motor; fluid pressure actuated means 125
- controlling said mechanism; a suction priming pump connected to the rotary pump; and controlling devices starting the suction pump acting through said means starting the rotary pump and then stopping the suc- 130

17. In a pump controlling mechanism, the combination of a rotary pump; a main electric motor driving said pump; a suction priming pump connected to the rotary pump; an auxiliary electric motor driving the suction pump; a liquid level controlled circuit for the auxiliary motor; a secondary circuit for the main motor; and devices controlling the secondary circuit controlled by fluid pressure from said pumps.
18. In a pump controlling mechanism, the combination of a rotary pump; a main electric motor driving said pump; a suction priming pump connected to the rotary pump; an auxiliary electric motor driving the suction pump; a liquid level controlled circuit for the auxiliary motor; a secondary circuit for the main motor; and devices controlling the secondary circuit controlled by suction pressure from the suction pump.
19. In a pump controlling mechanism, the combination of a rotary pump; a main electric motor driving said pump; a suction priming pump connected to the rotary pump; an auxiliary electric motor driving the suction pump; a liquid level controlled circuit for the auxiliary motor starting said motor; a secondary circuit for the main motor; fluid actuated devices from the pumps controlling said secondary circuit; and a liquid level device opening said circuit to stop the main motor.
20. In a rotary pump, the combination of a main electric motor driving said pump; a suction priming pump connected to the rotary pump; an auxiliary electric motor driving the suction pump; a liquid level controlled circuit for the auxiliary motor; a secondary circuit for the main motor; a switch having a starting and normal running position for the main motor; and fluid actuated means controlled by said pumps for actuating said switch to start the main motor in sequence with the auxiliary motor.
21. In a rotary pump, the combination of a main electric motor driving said pump; a suction priming pump connected to the rotary pump; an auxiliary electric motor driving the suction pump; a liquid level controlled circuit for the auxiliary motor; means for closing the connection between the priming pump and the rotary pump; a secondary circuit for the main motor; a switch controlling the secondary circuit; and fluid actuated means controlling the switch to start the main motor for closing the connection.
22. In a pump controlling mechanism, the combination of a rotary pump; a motor driving said pump; a circuit controlling the motor; and devices for opening the circuit comprising a liquid level actuated mechanism and a pumped liquid pressure actuated mechanism whereby said motor is stopped either by a pre-determined level of liquid or 65 a breaking of the liquid column leading to the pump.
23. In a pump controlling mechanism, the combination of a main pump; a motor driving said pump; starting mechanism for said 70 pump; and an auxiliary pump controlling said starting mechanism.
24. In a pump controlling mechanism, the combination of a main pump; a motor driving said pump; starting mechanism for said 75 pump; an auxiliary pump controlling said starting mechanism; and liquid level controlled means controlling the auxiliary pump.
25. In a pump controlling mechanism, the 80 combination of a main pump; a motor driving said pump; starting mechanism for said pump; an auxiliary pump controlling said starting mechanism; and means responsive to the action of the main pump stopping the 85 auxiliary pump.
26. In a pump controlling mechanism, the combination of a main pump; a motor driving said pump; means for supplying fluid under pressure; mechanism controlling said 90 pump; and fluid pressure actuated devices supplied from said means controlling said mechanism.
27. In a pump controlling mechanism, the 95 combination of a main pump; a motor driving said pump; an auxiliary pump; mechanism controlling said motor; and devices actuated by the pumped fluid of the auxiliary pump actuating said mechanism.
28. In a pump controlling mechanism, the 100 combination of a main pump; a motor driving said pump; mechanism controlling said motor; fluid actuated means controlling said mechanism; an auxiliary pump supplying said fluid; and controlling devices starting the auxiliary pump and acting through said 105 means starting the motor and then stopping the auxiliary pump.
29. In a pump controlling mechanism, the 110 combination of a main pump; a motor driving said pump; mechanism controlling said motor; fluid actuated means controlling said mechanism; an auxiliary pump supplying said fluid; and controlling devices starting the auxiliary pump and acting through said 115 means starting the motor and then stopping the auxiliary pump, said devices comprising mechanism responsive to liquid levels.
- In witness whereof, I have hereunto subscribed my name.

BAYARD M. HORTER.
